UNITED STATES PATENT OFFICE.

GRENVILLE MELLEN, OF EAST ORANGE, NEW JERSEY.

CASTING-POT.

1,216,341.

Specification of Letters Patent. Patented Feb. 20, 1917.

Application filed June 29, 1914. Serial No. 848 012.

To all whom it may concern:

Be it known that I, GRENVILLE MELLEN, a citizen of the United States, residing at East Orange, in the county of Essex and State of New Jersey, have invented certain new and useful Improvements in Casting-Pots, of which the following is a specification.

My invention relates to an apparatus for delivering molten metal from a casting-pot by pressure produced within the pot; and may be considered as an improvement of the device shown in my prior Patent 1,053,948, patented February 8, 1913.

My invention relates to the provision of means for producing pressure within the pot, means for sealing the pot, means for delivering metal from the pot, and to a co-ordinated mechanism for enabling these means to operate in proper relation to safely and economically deliver the molten metal or other material from the pot to the place of use. These and other features of my invention are pointed out in the claims attached to this specification, which fully describes the invention, in connection with the accompanying drawings, in which,—

Figure 1 is a plan view of the machine;

Fig. 2 is an end elevation, part of the casing being broken away and the melting-pot shown in section;

Fig. 3 is a side elevation, with the hood partly broken away, of the machine with the parts in casting position;

Fig. 4 is a side elevation, like Fig. 3, but showing the mechanism in the pot-charging position;

Fig. 5 is a vertical section through the casting-pot; and

Fig. 6 is a detail of the pump-lifter mechanism.

Referring to the drawings, the casting-pot 1 is suitably supported over a furnace 2, which may be of any suitable construction. 45 3 is a hood, covering the casting-pot, and has an exit flue 4. During the discharge of molten metal from the pot the lid 5 is held tightly against the inner face of the wall of an opening in the upper portion of the pot (see Fig. 5). These co-operating surfaces are preferably provided with a co-operating ridge and depression, as indicated in dotted lines. This lid is mounted with some slight play to enable it to adjust itself to form a 55 tight closure, on the end of the curved arm 6,

which is keyed onto shaft 7, journaled in bearings 8, 8, or the top of the pot, and 9 to one side thereof. Secured to the shaft 7 is a forked tilting arm 10, and to this arm is pivoted by bolt 12, the forked link 11, in turn pivoted to the discharge-pipe arm 13. The bolt 12 passes through a slotted block 14, carried at the top of the piston-rod 15 of a hydraulic cylinder 16, the piston of which is moved up and down by means of fluid pressure controlled by the cock 17. The arm 13 at its lower end is secured to the discharge pipe 75. At its inner end, this pipe is curved, as shown in Fig. 2, to conform to the inner curvature of the pot, and has a horizontal portion extending through the side of the pot and into the delivery pipe 17'. In order to discharge sufficient water into the casting-pot, so that the steam pressure produced will force out the molten metal, I provide a cylinder 18, having therein a piston, whose piston rod 19 has at its upper end a platform 20, carrying weights 21. Water is admitted to the cylinder from pipe 22 through a suitable check valve (not shown) and delivered therefrom through pipe 23 and valve 24 into the pot 1.

The arm 13 has at its end a hook 25, which when the arm swings down, engages a yielding latch 26, normally held in outward position by spring 27, this latch (see Fig. 6) being mounted on the pump-lifter arm 28 pivoted at 30. The forked outer end of the arm 28 straddles the piston rod 19 and when it rises, lifts the platform 20 and the attached piston rod 19. 31 is a spring buffer for arm 28, when it drops back. 32 is a pressure relief valve, from which any excess pressure fluid is delivered through pipe 33.

The device operates as follows:—

Assuming the parts to be in the position shown in Fig. 4, the opening in the top of the pot will be open, with the lid 5, arm 6, and discharge pipe 75 in the dotted line position of Fig. 5. The pot can then be charged with molten metal or metal to be melted. The operator then by operating the valve 17, admits pressure fluid into cylinder 16 to raise the piston rod 15, thereby changing the position of arm 10 from that shown in Fig. 4 to that of Fig. 3, thus bringing the lid 5 into the closed (full line) position (Figs. 2 and 5) and rotating the discharge pipe 75, so that it is lowered into molten metal in the pot (Figs. 2 and 5). At the

same time, the link 11 rotates the arm 13, which, the hook 25 and latch 26 being in engagement, raises arm 28, which, in turn raises the piston rod 19, and the weights carried thereby to the position shown in Fig. 3. The rising piston sucks water through pipe 22 into the cylinder, the check valve holding it therein. As the arms 13 and 28 are pivoted on different centers, the hook 25 will, as the two arms rotate, move outward along the under surface of the latch, and when the arm 28 has been raised to the desired height, release the arm 28, which drops back to its original position.

15 The cylinder 18 now contains water under pressure of the accumulator weights 21, and the lid on the pot is held tightly closed by the hydraulic pressure in cylinder 16. The cylinder 18 is so proportioned as to contain 20 the requisite amount of water to furnish sufficient pressure, when vaporized in the pot, to eject all the molten metal through discharge pipe 75 and delivery pipe 17. The operator now opens valve 24, and the 25 water is forced from the cylinder through pipe 23 into the space above the molten metal in the pot, where the heat vaporizes it and the pressure developed ejects the molten metal. The valve 24 may of course 30 be closed at any time, thus stopping the flow of water. Sufficient weights 21 are used to counterbalance the developed pressure in the pot. When the metal has been delivered from the pot, the operator, by reversing 35 valve 17, can cause the hydraulic mechanism to restore the parts to the open-lid position, ready for a new charge.

Any excess pressure is relieved through safety-valve 32.

40 By the mechanism above described, the operation of casting is effected with a minimum of labor, expense and fuel, with an increase of capacity.

Only one operation, the turning of a 45 valve, is required to set the mechanism for charging with metal; and a second operation, the turning of another valve, to deliver the molten metal to the casting machine, or other place of use.

50 While I have described in detail a mechanism suitable for carrying out the purpose of this invention, it is obvious that other equivalent mechanical devices may be employed, and that instead of employing a 55 hydraulic operating mechanism, the lever system may be operated by any other power, such as steam or electricity or by hand; and further that while my invention is intended primarily for use with molten metals, it 60 is applicable for use with other materials at high temperatures.

I claim:—

1. In a casting machine, the combination of a melting-pot, a closure therefor, a pump, 65 a valve controlled conduit connecting the

pump to the melting-pot, and means connected and arranged to coincidentally operate the closure and the pump.

2. In a casting-machine, the combination with a melting-pot, a discharge pipe therefrom, of a pumping device comprising a piston and a weighted piston rod, a valve-controlled conduit connecting the discharge of the pump and melting-pot, and means for operating the pumping device.

3. In a casting-machine, the combination with a melting-pot, a discharge pipe therefrom and a closure therefor, of a pumping device comprising a piston and a weighted piston rod, a valve-controlled conduit connecting the pump and melting-pot, and means connected and arranged to coincidentally operate the closure and the pump.

4. In a casting-machine, the combination with a pot, of a movable closure therefor, a discharge pipe rotatably mounted in said pot and means connected and arranged to simultaneously operate the closure and discharge pipe.

5. In a casting-machine, the combination with a pot, a movable closure therefor, and means for introducing fluid into the melting-pot, of a discharge pipe rotatably mounted in said pot, and means connected and arranged to simultaneously operate the closure and discharge pipe.

6. In a casting-machine, the combination with a pot, a movable closure therefor, and a pump for introducing fluid into the melting-pot, of a discharge pipe rotatably mounted in said pot, and means connected and arranged to simultaneously operate the closure and discharge pipe.

7. In a casting-machine, the combination with a casting-pot of a movable closure therefor, a pump-cylinder having a weighted piston rod, a discharge pipe rotatably mounted in said pot, a valved conduit connecting the pump cylinder and pot, power mechanism connected to operate said closure and discharge pipe, and a lever detachably connected to said power mechanism for operating said pump.

8. In a casting-machine the combination with a casting-pot of a pivoted closure therefor, a discharge pipe rotatably mounted therein, a power mechanism, levers connecting the power mechanism to the closure and discharge pipe, a pump, a piston rod therefor, a pivoted lever for operating said piston rod, and coöperating engaging means on the discharge pipe lever and the pivoted lever.

9. In a casting machine, the combination with a casting-pot of a closure therefor, a rotatable discharge pipe mounted in said pot, a pump, a conduit connecting the pump and pot, and mechanism connected and arranged to coincidentally operate the discharge pipe and pump.

10. The combination with a casting-pot

- having an opening therein, of a closure therefor, a discharge pipe therefrom, a pump having a weighted piston rod, a valved conduit connecting the discharge of the pump and pot, and means for raising the piston rod.
11. In a casting-machine, a casting-pot having an opening therein, a pivoted lid fitting against the inner wall of said opening, and mechanism for operating said lid.
12. In a casting machine, a casting pot, a discharge pipe having a horizontal portion passing through and journaled in the walls of said pot, and a depending portion arranged to extend downwardly into the pot, and means for rotating the pipe about its horizontal portion, whereby the depending portion is raised above the level of the metal.
13. In a casting machine, a casting pot, a discharge pipe having a horizontal portion passing through and journaled in the walls of said pot, and a depending portion arranged to extend downwardly into the pot and shaped to conform to the inner wall of the pot, and means for rotating the pipe about its horizontal portion, whereby the depending portion is raised above the level of the metal.
14. A casting-pot having a curved upper portion, an opening to one side thereof, a curved arm carrying a lid and pivoted on said pot, said lid arranged to engage the inner wall of said opening in the closed position and to move back against the inner wall of the pot in the open position.
15. A casting-pot having a curved upper portion, an opening to one side thereof, a curved arm carrying a lid and pivoted on said pot, said lid arranged to engage the inner wall of said opening in the closed position and to move back against the inner wall of the pot in the open position, and a discharge pipe rotatably mounted on said pot.
16. A casting-pot having a curved upper portion, an opening to one side thereof, a curved arm carrying a lid and pivoted on said pot, said lid arranged to engage the inner wall of said opening in the closed position and to move back against the inner wall of the pot in the open position.
- of the pot in the open position, a discharge pipe rotatably mounted on said pot, and means for coincidentally operating said lid and discharge pipe.
17. In a casting machine, the combination of a melting-pot, a closure therefor, a pump, a conduit connecting the pump to the melting-pot, and means connected and arranged to coincidentally operate the closure and the pump.
18. In a casting-machine, the combination with a melting pot, a discharge pipe therefrom, of a pumping device outside the pot comprising a piston and a weighted piston rod, a conduit connecting the discharge of the pump and melting-pot, and means for operating the pumping device.
19. In a casting-machine, the combination with a melting pot, a discharge pipe therefrom and a closure therefor, of a pumping device comprising a piston and a weighted piston rod, a conduit connecting the pump and melting-pot, and means connected and arranged to coincidentally operate the closure and the pump.
20. In a casting-machine, the combination with a casting pot of a movable closure therefor, a pump-cylinder having a weighted piston rod, a discharge pipe rotatably mounted in said pot, a conduit connecting the pump cylinder and pot, power mechanism connected to operate said closure and discharge pipe, and a lever adapted to be detachably connected to said power mechanism for operating said pump.
21. The combination with a casting-pot having an opening therein, of a closure therefor, a discharge pipe therefrom, a pump outside the pot having a weighted piston rod, a conduit connecting the discharge of the pump and pot, and means for raising the piston rod.

In testimony whereof I affix my signature in presence of three witnesses.
